UNITED STATES PATENT OFFICE.

LESTER S. QUENSEL, OF EVANSTON, ILLINOIS.

UNCOUPLING DEVICE FOR CARS.

1,085,940.

Specification of Letters Patent.

Patented Feb. 3, 1914.

Application filed May 5, 1911, Serial No. 625,190. Renewed December 8, 1913. Serial No. 805,433.

To all whom it may concern:

Be it known that I, LESTER S. QUENSEL, a citizen of the United States, residing at Evanston, in the county of Cook and State 5 of Illinois, have invented a new and useful Improvement in Uncoupling Devices for Cars, of which the following is a specification.

My object is to provide certain improvements in the construction of uncoupling lever-mechanism for railway-cars, with a view to rendering the same particularly simple, strong, durable and well adapted for its purpose.

15 In the drawing—Figure 1 is a plan view of the uncoupling device applied to a freight-car end; Fig. 2, a view of the same in front elevation; and Fig. 3, a side elevation of the same.

20 The uncoupling shaft 4 is journaled in brackets 5, 6 secured against the end-sill 7 of the car-frame. The shaft is bent along its inner end-portion to form the horizontally extending arm 8, and is bent along its 25 outer end-portion to form the downwardly extending operating crank or handle 9 provided with the bend 10.

The numeral 11 designates a bar bent, as indicated, to form the downwardly-inclined 30 outer end-portion 12 provided with an opening through it for the shaft 4, a looped portion 13 forming a shoulder resting upon the shaft 4, and an angular portion 14 resting upon or extending across the path of the 35 arm 8. The inner end of the bar 11 is formed with a hook 15 engaging the eye of the locking-pin 16, the hook-forming end-portion of the bar being tapered, and also inclined laterally with relation to the body 40 of the bar, as indicated in Fig. 1. The bend 10 in the handle bears normally against the surface of the sill 7 to hold the handle-portion 9 vertical and cause the arm 8 to extend horizontally.

45 By swinging the handle 9 to the right in Fig. 3 the shaft 4 is turned to raise the arm 8 and through the latter to raise the bar 11 on the pivot formed by the shaft 4 and lift the locking-pin to unlock the coupler 17 in

the usual manner. To compensate for the 50 lateral swinging of the draw-bar, carrying the coupler 17, when the car is rounding curves, it is necessary that the bar 11 should slide readily along the shaft 4, and to admit of this the opening through the part 12 55 should be materially larger than the diameter of the shaft.

My improved uncoupling-device differs only in certain details of construction from other devices for the same purposes commonly employed on railway-cars, and my improvements are intended to overcome certain faults which experience has rendered apparent in the uncoupling devices hitherto provided. For example, it happens quite 60 frequently in railway practice, and especially in the case of very long and heavy trains, that drawbars are pulled out causing breakage of the uncoupling devices and the dropping of the pin-raising bar upon the 65 track, with attendant danger of derailing the cars. By providing the shoulder formed by the loop 13 in the bar 11, and causing it to rest upon the shaft 4, the bar 11 when lifted by the arm 8 is prevented from turning between its ends without lifting the locking-pin; and in case that the drawbar is pulled out as before stated, the bar 11 when swung past the end of the arm 8 will 70 turn on its pivot at 12 in a manner to cause 75 the inclined hook 15 to release itself from the locking-pin to avoid breaking of the bar 11, and cause the latter to hang suspended from the shaft 4 instead of being cast upon the roadbed.

The foregoing description is intended to convey a clear understanding of my improvements in what I now believe to be the best form of their embodiment, and no undue limitation should be understood therefrom. It is my intention to claim all that is novel in my invention, and that the claim shall be construed as broadly as the prior state of the art may warrant.

What I claim as new and desire to secure 95 by Letters Patent is—

In an uncoupling-device for car-couplers, the combination with the car-frame

and locking-pin, of a rock-shaft, journaled in bearings on the car-frame, formed with a handle at its outer end and a laterally-extending arm at its inner end, and a bar, between its ends extending in the path of said arm, at its inner end releasably engaging said locking-pin, provided at its outer end with means for pivotally and slidably en-

gaging said shaft, and provided, between its outer end and the path of said arm, with a shoulder resting against said shaft.

LESTER S. QUENSEL.

In presence of—

A. U. THORIEN,
R. A. SCHAEFER.
